FIG. 1.

FIG. 2.

FIG. 3.

Charles V. Wright,
By Chauff Williamson
Attorney

UNITED STATES PATENT OFFICE.

CHARLES V. WRIGHT, OF REYNOLDS, PENNSYLVANIA.

SHAKING-SCREEN.

1,228,277.

Specification of Letters Patent. Patented May 29, 1917.

Application filed October 5, 1916. Serial No. 123,944.

To all whom it may concern:

Be it known that I, CHARLES V. WRIGHT, a citizen of the United States, and resident of Reynolds, in the county of Schuylkill, 5 and in the State of Pennsylvania, have invented a certain new and useful Improvement in Shaking-Screens, and do hereby declare that the following is a full, clear, and exact description thereof.

10 My invention relates to the plates of shaker screens for washing coal and ores, and generally stated the object of my invention is to provide a construction which will effect the desired agitation of the material 15 and assure its distribution uniformly over the plate, preventing banking of the material at the sides, and to this end and for the attainment of other objects, which will be evident to those skilled in the art from the 20 detailed description hereinafter given, my invention consists in the shaker plate having the characteristics of construction substantially as hereinafter specified and claimed.

In the accompanying drawings is illustrated a preferred embodiment of my invention, in which drawings—

Figure 1 is a top plan view of a shaker plate embodying my invention;

Fig. 2 is a section on the line 2—2 of 30 Fig. 1.

My invention has to do with that type of shaker plate having riffles on its surfaces and perforated for the passage from the plate of fine material. A series of such 35 plates, oblong in form, are placed edge to edge to extend over the desired area, and are supported, as usual, by a suitable framing in a box. I consider it necessary to illustrate my invention to show in the drawings 40 merely one plate, since my invention has to do only with the configuration of the surfaces over which the material passes and has nothing to do with the manner of mounting, or supporting the plates. The plate 10 45 shown in the drawings, is oblong in form, its longer dimension being crosswise of the direction of travel of the material. As shown in the drawings there are two parallel rows of riffles 11, the rows extending 50 transversely, and the riffles being formed of units that are V-shaped with one arm, or leg of the V longer than the other, and the units of a row being so relatively situated that the extremity of the longer leg 55 projects beyond the shorter leg of an adjacent unit. Preferably the riffles of a series upon opposite sides of the median line, con-

sidered transversely of the plate, are in reversed arrangement, that is to say, the longer legs of one group of riffles on one 60 side of said median line extend in the same direction as the shorter legs of the other set of riffles on the other side of said median line, and the shorter legs of the riffles of one row extend in the same direction as the 65 longer legs of the riffles of the other row.

Preferably the short leg of a unit joins the long leg a short distance from one end of the leg so that there is a lateral projection 12 at the apex of the V. 70

The riffles are formed by corrugating the plate so that they present convexly curved ribs on the material-engaging side of the plate, and a substantially flat, or plane surface is provided around and between the 75 riffles. The apexes of the V-shaped units point in the direction of flow of the material over the plate, so that the legs of each unit converge onward and laterally and there is a more or less open channel afforded between 80 adjacent units in the same row by the rounding of the extremity of a short leg near the long leg of an adjacent unit as well as by a clear space between such extremity and the adjacent long leg, and the apexes 85 of the units of the first row are to one side of the beginning of the long legs of the units of the next row, so that material passing from the units of the first row is intercepted by the long legs of the units of the 90 second row, and by reason of the inclination inward, or in the opposite direction from that of the long legs of the unit of the first row, the direction of travel of the material is changed so that while moving 95 onward it is also moved inward away from the side of the plate and thus whatever outward tendency might have been imparted to it by the long leg of the unit of the first row is counteracted. In fact the flow from 100 one unit of the first row is intercepted by the long legs of two adjacent units of the second row.

It will be seen that by reason of the inclination of the legs of each unit with reference to each other, the relative arrangement of the units of each row and the relative arrangement of the two rows, coal, for example, in passing over the shaker plate and encountering the riffles, will strike numerous oppositely extending inclined surfaces, reaching transversely across the plate which will subdivide the mass, or stream of material into numerous smaller streams, 105 110

which will be confined within comparatively narrow limits transversely of the plate, while moving freely back and forth transversely, and thus any movement of a substantial body of material toward either side which would result in its banking on either side, is prevented, and a practically uniform distribution of the material over the shaker plate as it passes over the latter will be secured. Furthermore, a desirable tumbling action of the riffles on the coal is secured, and by reason of the plane surfaces on the plate between the riffles, opportunity for fine material to pass through the holes therein is afforded. Since there is no tendency of the material to bodily movement to either side of the plate with resulting banking, or, accumulation thereof, it is not necessary to provide any special means, as by a particular formation of a succeeding plate, to counteract that tendency, and, hence, all the plates, where my invention is employed, may be alike,—an obviously important advantage from both the manufacturer's and user's standpoint.

As shown in Fig. 3 I may employ riffles 13 that are V-shaped with legs of substantially the same length, and with apexes pointing toward the material as it flows upon the plate, and these riffles may have the double arrangement shown. As their legs diverge outwardly with reference to the flow of material over the plate they act to spread the material laterally as it enters upon the plate to a greater extent than the form of riffles in the first row shown in Fig. 1.

Having thus described my invention what I claim is—

40 1. A shaker plate having rows of riffles composed of oppositely diverging legs, the rows being arranged progressively one after another in the direction of flow of material over the plate, and the plate having surfaces between the legs of adjacent riffles of the same row and the legs of adjacent rows forming paths for the passage of material between riffles of the same row and between the rows of riffles.

50 2. A shaker plate having rows of riffles composed of oppositely diverging legs, the rows being arranged progressively one after another in the direction of flow of material over the plate, and the plate having surfaces between the legs of adjacent riffles of the same row and the legs of adjacent rows forming paths for the passage of material between riffles of the same row and between the rows of riffles, said legs being of unequal length, and the longer leg of one set extending past the shorter leg of an adjacent set.

60 3. A shaker plate having rows of riffles

composed of oppositely diverging legs, the rows being arranged progressively one after another in the direction of flow of material over the plate, and the plate having surfaces between the legs of adjacent riffles of the same row and the legs of adjacent rows forming paths for the passage of material between riffles of the same row and between the rows of riffles, said legs being of unequal length, and the longer leg of one set extending past the shorter leg of an adjacent set, said riffles being arranged in a row formed of groups with the short legs of one group extending in the same direction as the long legs of an adjacent group.

4. A shaker plate having parallel rows of riffles formed of V-shaped units, each unit having a short leg and a long leg, spaces being provided between the units of a row and between the rows of units, that form zigzag paths between adjacent units of the same row and between adjacent rows of units.

5. A shaker plate having parallel rows of riffles formed of V-shaped units, each unit having a short leg and a long leg, spaces being provided between the units of a row and between the rows of units, that form zigzag paths between adjacent units of the same row and between adjacent rows of units, and the long legs of the units of one row extending in the same direction as the short legs of the units of an adjoining row.

6. A shaker plate having parallel rows of riffles formed of V-shaped units, each unit having a short leg and a long leg, spaces being provided between the units of a row and between the rows of units, that form zigzag paths between adjacent units of the same row and between adjacent rows of units, the plate having a plane perforated surface between the rows of riffles.

7. A shaker plate having its top surface over which material flows formed of riffles integral with the plate that are raised above adjacent surfaces of the plate, said riffles being arranged in rows progressively one after another in the direction of flow of material over the plate, the riffles of each row being composed of oppositely diverging legs, the divergence being opposite the direction of flow of material over the plate, the riffles of a row being spaced apart and the rows of riffles being spaced apart.

In testimony that I claim the foregoing I have hereunto set my hand.

CHARLES V. WRIGHT.
